SIPHON BOTTLE

George J. Meyer, Milwaukee, Wis.

Application March 1, 1933, Serial No. 659,159

10 Claims. (Cl. 215—5)

This invention relates to siphon bottles, and more particularly to a siphon bottle having a novel valve and control structure.

An object of the invention is to provide a siphon head having a valve adjacent the outer end of the spout, thereby preventing entry therein of foreign matter. Devices of the type now in use ordinarily have a spout of considerable length, open to contamination from without, with the valve located at the inner end thereof.

Another object is to provide a siphon head and bottle adapted to dispense its contents without contact of the latter with metal parts or mechanism. Other products of the type commonly have metallic mechanism within the head with which the contents of the bottle must unavoidably come into contact.

Another object is to provide a valve which may be inserted in a one-piece bottle and siphon head of vitreous or non-metallic material, after the latter has been completely formed.

Another object of the invention is to provide a siphon head which may be constructed of relatively inexpensive materials. Siphon heads have heretofore been made of pure block tin, and are often the object of theft because of the value of the metal contained therein.

With these and other objects in view, the invention consists in the construction and combinations of elements hereinafter described and particularly pointed out in the claims.

In the drawing:—

Fig. 1 represents a fragmentary vertical sectional view of a siphon bottle embodying my invention.

Fig. 2 shows the device applied to a siphon bottle constructed of vitreous or non-metallic material with a zinc or other simple metal die casting encasing the head to fulcrum the lever.

Fig. 3 shows the device applied to a bottle formed entirely of vitreous or non-metallic material having ears raised on the head from the substance thereof in which the lever is fulcrumed.

Fig. 4 is a perspective view of the siphon head showing the manner of coupling the sleeve and lever.

Fig. 5 is a view in vertical section and Fig. 6 is an end view in elevation of the valve structure.

Referring more particularly to the drawing, in the form shown in Fig. 1, a bottle 10 is provided with a delivery or siphon tube 11. An exteriorly threaded split ring 12 is placed on the neck of the bottle 10. The spout 13, of vitreous or non-metallic material, enveloped by a zinc or other

metal die casting 14, threaded at 15, is turned on securely by means of the split ring 12.

A lever 16, having a coiled pressure spring 17 partially concealed within the body thereof, is fulcrumed in the ears 18, of the metal casting 14.

A sleeve, 20, is pivotally secured to lever 16 by means of the connecting arms 21, and the pin 22. The sleeve 20 has a reduced opening at 23 and carries the internal washer 24 formed preferably of a rubber or fibrous material.

A valve stem 25 embraced at its outer end by the ring 26, is fixedly secured within the opening 23 of sleeve 20, by means of the cross bar 27, as shown in Fig. 5. The valve stem 25 is preferably made of stainless or corrosive resisting metal, and has an integrally formed, enlarged head 28.

A coating 30, of rubber or other resilient material, envelopes the head 28. The coating or envelope 30 is disposed on said head unequally, to the effect that the greater body thereof is deposited on the seating side of the valve head, with the inner half of the latter covered thinly as at 31 of Fig. 5. The spout 13 has an opening at 32, the diameter of which is only slightly less than the diameter of the head 28 including its envelope or coating 30. It will readily be understood that in assembling the device, the valve head, because of the inequality in thickness of its envelope, may readily be inserted into the opening at 32 of spout 13, but will resist all attempts to remove it without actual destruction of the said coating 30.

In use, the bottle may be filled in the conventional manner by subjecting the opening at 23 to the pressure filling means. In this operation the sleeve 20 is forced backwardly and the washer 24 is brought into close contact with the end of the spout 13, thereby preventing any escape of the liquid while it is being forced under pressure into the bottle.

After the filling has been completed, the pressure of spring 17 in the lever 16 normally maintains the sleeve 20 in its extended position, in which a tension is exerted on the stem 25 to seat the valve head 28 firmly inside of spout 13 to close the opening of the latter at 32, thus preventing escape of the contents. A manual pressure downwardly of the lever 16 serves to retract the sleeve with a consequent unseating of the inner valve 28 and release of the contents.

The bottle shown in Fig. 2 is constructed of vitreous material welded to form a unitary structure. A metal casting 14 is applied to the spout 13 as a reinforcement. The manner of inserting the valve described above is the only way in

which it can be placed within this form and the modification shown in Fig. 3. The latter is formed entirely of vitreous material and is minus the metal casting reinforcement. A pair of ears, 5 18, drawn up on the top of the spout 13, serves to fulcrum the lever 16.

It is to be understood that the device is capable of various modifications in structure without departing from the spirit of the invention or the 10 scope of the appended claims.

Having thus described my invention, what I claim and desire to secure by Letters Patent of the United States, is:

1. In a siphon head, a spout having a closure 15 therein, a closure valve movable axially within the passage in said spout at the outer end thereof, manually operable rockable means mounted on the head, sleeve means coupling said valve and the rockable means disposed externally of said spout for effecting axial movement of said valve with the manually operable means, the said sleeve projecting beyond the outer end of said spout and having an inner annular washer for sealing the sleeve with the end of the spout.

2. In a siphon head, a spout having a passage 20 therein, a closure valve movable axially within the passage in said spout adjacent the outer end thereof, manually operable rockable means mounted on the head, and external sleeve means 30 connecting said manually operable rockable means and said valve to operate the latter, the said sleeve means projecting beyond the outer end of said spout, a reduced portion in the outer end of the sleeve means, and an inner annular washer 35 within the reduced portion for sealing the latter with the end of the spout.

3. In a siphon head, a spout having a reduced 40 outlet opening, a valve movable axially in said opening and adapted to seat interiorly of said opening, manually operable rockable means mounted on the head, external sleeve means connecting said manually operable rockable means and said valve to operate the latter, the said sleeve projecting beyond the outer end of the spout, a 45 reduced portion on the outer end of the sleeve, and an annular washer in the sleeve for sealing the latter with the outer end of the spout when the valve is open.

4. In a siphon head, a spout having a reduced 50 outlet opening, a valve axially movable and normally seated interiorly of and closing said opening, an ellipsoidal head on said valve, a covering of resilient material enveloping said head, a stem integral with said head and protruding 55 outwardly through said opening, manually operable rockable valve operating means mounted on the head, and external sleeve means connecting said manually operable rockable means with said valve to operate the latter.

60 5. In a siphon head, an ellipsoidal valve head, a spout with a reduced opening slightly larger than the valve head, a resilient coating envelop-

ing said valve head, an enlargement of said coating on a side of said valve head, whereby the latter may be moved through the spout opening in one direction only.

6. In the siphon head, a spout having a passage therein, a cylindrical sleeve enveloping the outer end of said spout, a washer within said sleeve for effecting a seal with the outer end of said spout, a stem on said sleeve element for axial movement within the passage in said spout, a valve on said stem adapted to seat interiorly of said passage, rockable means on said head operable in one direction to effect axial movement of said sleeve element to seat said valve in said passage, and operable in the other direction 10 to seat said washer on said spout.

7. In the siphon head, a spout having a passage therein, an opening at the mouth of said spout, an enlarged recess in said passage adjacent said opening, an axially movable element 20 surrounding said spout, a washer carried by said element, a valve on said stem adapted to normally lie within said recess, and rockable means on said head adapted to effect movement of said element in one direction to effect a sealing contact between said valve and said passage and in the other direction to effect contact between said washer and the end of said spout.

8. In a siphon head, a spout having a passage 30 therein, an axially movable element surrounding said spout, a valve stem carried by said element, an annular member within said element surrounding said stem, a valve means on said stem adapted to control the flow of liquid through the passage in said spout, rockable means on said head adapted to normally effect movement of said element in one direction to effect sealing contact between said valve and said passage, and in the other direction to effect contact between 35 said annular member and the end of said spout.

9. In a siphon head, a spout having a passage 40 therein, a closure valve movable axially within the passage in said spout adjacent the outer end thereof, manually operable rockable means mounted on the head, an axially movable element 45 surrounding said spout, means connecting said manually operable means and said valve, and a sealing member within said axially movable member adapted for contact with the end of the spout when said valve means is in open position.

10. In a siphon head, a spout having a passage 50 therein, a manually operable rockable means mounted on the head, an axially movable element surrounding said spout, a valve means carried by said element, said valve means adapted to control the opening and closing of the passage in said spout, and a sealing member on said axially movable element, said sealing member adapted to contact the mouth of said spout when said valve means is in open position.

GEORGE J. MEYER.
